DESIGN FOR A KNITTED FABRIC OR SIMILAR ARTICLE

Arthur Henry Ernest Stabenow, Portland, Oreg.

Application October 10, 1935, Serial No. 58,930

Term of patent 3½ years

To all whom it may concern:

Be it known that I, Arthur Henry Ernest Stabenow, a citizen of the United States, residing at Portland, Oregon, have invented a new, original, and ornamental Design for a Knitted Fabric or Similar Article, of which the following is a specification, reference being had to the accompanying drawing, forming a part thereof.

The figure is a plan view of a knitted fabric showing my new design.

I claim:

The ornamental design for a knitted fabric or similar article, as shown.

In testimony whereof I have signed this specification.

ARTHUR HENRY ERNEST STABENOW.
